UNITED STATES PATENT OFFICE.

GUSTAV A. HUBER, OF NEW YORK, N. Y., ASSIGNOR TO HUBER AUTOMATIC MAGNETO SIGNALING COMPANY, OF NEW YORK, N. Y., A CORPORATION OF NEW YORK.

ELECTRIC GENERATOR.

942,325.

Specification of Letters Patent.

Patented Dec. 7, 1909.

Application filed February 10, 1908. Serial No. 415,199.

To all whom it may concern:

Be it known that I, GUSTAV ADOLPH HUBER, a citizen of the United States, residing at New York, in the county of New York and 5 State of New York, have invented new and useful Improvements in Electric Generators, of which the following is a specification.

This invention relates to electric generators and more particularly to that class 10 of machines adapted to be actuated by hand power for the purpose of furnishing a small current of comparatively brief duration, when desired. As heretofore constructed, such devices have been provided with a 15 manually operable lever or handle, which, by means of suitable gearing, imparts rotation to the armature of a small generator, usually of the magneto type. It is frequently desirable, however, to maintain the 20 generation of current in such a machine for a considerable period, and for practical reasons, undesirable to compel the operator to continue to manipulate the handle during such period.

25 It is the primary object of the present invention, therefore, to produce a machine whereby a momentary actuation of the handle or lever will serve to effect the generation of current for a considerable period, after the actuation of the lever has ceased.

A further object of the invention is to provide mechanism whereby the generator will, at each actuation, be driven for practically the same length of time regardless 35 of the force used in manipulating the lever.

With the above and other objects in view and to improve generally upon the details of construction of such machines, my invention consists in the construction and arrangement of parts hereinafter described 40 and illustrated in the accompanying drawings, in which:—

Figure 1 is a front elevation of my complete machine with the front wall of the 45 casing removed; Fig. 2 is a central transverse section thereof along the line 2—2 of Fig. 1, looking in the direction of the arrow; Fig. 3 is a view substantially at right-angles to Fig. 2, the casing being in section 50 on the line 3—3 of Fig. 1, and the mechanism being shown in elevation, with parts broken away; Fig. 4 is a detail of the pawl and ratchet mechanism employed.

Referring to the drawings in detail the

apparatus comprises a casing 1, preferably 55 of brass or similar material, and cylindrical in shape. This casing is provided with a front wall or cover 2 which, when in position, serves to inclose the mechanism entirely, and protect it from dust and dirt, 60 and also from being tampered with.

Against the rear wall of the casing 1 I secure the field magnet 3 of a magneto generator, the armature 4 of which is mounted between the poles of the field, and is preferably 65 inclosed in a casing 5, in which the shaft 6 is journaled. To one end of this shaft is secured a bevel gear 12, and an insulated contact 7, to which one end of the armature winding is connected, is carried by 70 the other end of the shaft, and bears against a contact spring 8 secured to a block of insulation 9. From this spring extends a connection to an insulated binding post 10, which forms one terminal of the circuit. 75 The other end of the armature winding is grounded on the frame of the machine and a binding post 11 is secured to the casing, and forms the other terminal of the circuit.

While I have shown and described a simple magneto for generating alternating currents, it is obvious that I may employ a direct current generator of any suitable type, if desired, as the generator itself forms no part of the present invention.

80 Supported by the rear wall of the casing is a stud shaft 13, set in a block 14. Mounted on ball bearings 15 on the shaft 13 is a fly-wheel 16, preferably of cast-iron or other heavy material. This fly-wheel is large and 85 heavy, as compared with the generator, and has secured to one side thereof a bevel gear 17 which meshes with the bevel gear 12, on the shaft of the generator. On the other side of the wheel 16 is secured a ratchet 90 wheel 18.

A swinging pawl 19 is pivoted on a stud 95 carried by a plate 24, which is mounted to swing on an axis concentric with the ratchet wheel 18. The pawl 19 is provided with a 100 tail or extension 20, adapted, when in its normal position, to rest against a lug 21 secured to the inside of the casing 1. This lug acts to hold the nose of the pawl out of engagement with the ratchet wheel, while a 105 spring 22 fixed to the plate 24 serves to urge the pawl into engagement with the ratchet wheel as soon as it is removed from the in-

fluence of the lug 21. The pawl 19 is spaced apart from the plate 24 by means of a sleeve 25 through which the stud 23 passes.

The plate 24 is secured to a bushing which 5 embraces a stud shaft 27, and at its other end this bushing carries a pinion 26. The stud shaft 27 is mounted in a cross-bar 28 secured by screws to opposite sides of the casing 1. A heavy coil spring 29 is attached at one end to the bushing above mentioned, and after being wound around this bushing between the pinion 26 and plate 24, is secured at its other end to a stud 30 set into the cross-bar 28. A bracket 31 is also 15 secured inside the casing, as by means of screws, and carries a bolt 32 which extends through the front wall 2 of the casing. Journaled on this bolt is a hub 33, carrying an arc-shaped rack 34, arranged to mesh 20 with the pinion 26. To the upper end of the hub 33 a lever or crank 35 is adapted to be secured by means of a nut 36. The lever is provided at its upper end with a suitable handle 37, and the front wall of the casing 25 carries two studs 38, spaced apart, and serving to limit the movement of the lever.

In operation, the lever is moved to the left, as indicated in Fig. 1, as far as the stud 38, 30 will permit and this, acting through the rack 34, and pinion 26 serves to put the spring 29 under strong tension. At the same time the plate 24 turns with pinion 26, and causes the swinging pawl 19 to travel around the edge of the ratchet wheel 18 in a direction opposite to that of the arrow in Fig. 4. When, 35 therefore, the handle 37 is released the nose of the pawl 19 engages one of the teeth of the ratchet wheel, and the spring 29, in unwinding, returns the lever 35 to its original 40 position, and at the same time, imparts an impulse to the fly wheel which is rigidly connected with the ratchet wheel 18. The fly-wheel is thus set spinning, and as it is of large size and weight compared with the 45 generator, and nicely mounted on ball bearings, it will continue to rotate for a considerable period of time, and, through the gears 17 and 12, actuate the armature 4 of the magneto and thus generate the desired current. 50 From the foregoing, therefore, it is obvious that the spring 29 serves as a storage device for the energy manually imparted to the lever, and that the energy so stored is potential. The fly-wheel or other similar momentum device also serves as a storage device for energy, but the energy so stored is kinetic. When the handle is released, the 55 potential energy of the spring is transformed into the kinetic energy of the momentum device, and this, in turn, is converted into electrical energy by the generator.

While I have shown and described the best form of my invention now known to me, many modifications within the scope of my 60 invention will suggest themselves to the

skilled engineer, and I desire to have it understood that I intend to cover by the annexed claims all such modifications.

What I claim is:—

1. In combination, an electric generator, 70 and means for actuating the same comprising a ratchet wheel connected with the armature thereof, a swinging pawl coöperating with said ratchet, a lever for actuating said pawl, and means for holding said pawl out 75 of engagement with said ratchet except when said lever is operated.

2. Mechanism for manually generating electric currents, comprising a suitable generator, a flywheel separate therefrom and 80 geared thereto, a ratchet wheel rigidly connected to said flywheel, a pawl in operative relation with said ratchet wheel, means for moving said pawl bodily so as to cause it to engage said ratchet wheel and impart an impulse thereto, and means for automatically 85 disengaging said pawl from said wheel after such impulse has been imparted.

3. Mechanism for manually generating electric currents comprising a suitable generator, a flywheel connected therewith, and 90 means for imparting an impulse to said wheel so as to cause it to spin and drive said generator, such means comprising a ratchet wheel, a spring pressed pawl associated 95 therewith, a pivoted bracket carrying said pawl, a spring normally urging said bracket toward one limit of its stroke, a lever for swinging said bracket to the other limit of its stroke and compressing said spring, such 100 spring, when the handle is released, serving to cause said pawl to engage and drive said ratchet wheel, and means for disengaging said pawl from the said wheel when the bracket has regained its original position. 105

4. Mechanism for manually generating electric currents, comprising a cylindrical casing, a flywheel mounted therein and 110 snugly fitting the same, a gear wheel secured to one side of said flywheel and a ratchet wheel to the other, a suitable generator in the casing driven by said gear wheel, a swinging pawl associated with said ratchet wheel, and means for so moving said pawl as to cause it to momentarily engage, 115 travel with, and then disengage said ratchet wheel, whereby said flywheel is caused to spin.

5. Mechanism for manually generating electrical currents comprising a cylindrical 120 casing, a generator armature mounted transversely of said casing, heads closing the ends of said casing, a field magnet for said generator armature, and a flywheel axially mounted on and supported by one of said heads, a motor mounted axially on and supported by the other head, gearing between said fly wheel and said generator, and gearing between said motor and said fly wheel. 125

6. Mechanism for manually generating 130

electrical currents comprising a cylindrical casing, a generator armature mounted transversely of said casing, heads closing the ends of said casing, a field magnet for said generator armature, and a fly wheel axially mounted on and supported by one of said heads, a motor mounted axially on and supported by the other head, gearing between said fly wheel and said generator, and gearing between said motor and said fly wheel, and means operable from without the cas-

ing for causing said motor to store up energy in said fly wheel for operating said generator.

In testimony whereof I have hereunto set 15 my hand in presence of two subscribing witnesses.

GUSTAV A. HUBER.
